(57) **CLAIM**

The ornamental design for the bottle, as shown and described.

DESCRIPTION

FIG. 1 is a right-side view showing my new bottle design, the left-side view thereof being a mirror image;

FIG. 2 is a front view thereof; and,

FIG. 3 is a front, top and right-side perspective view thereof; The broken lines are included for the purpose of illustrating portions of the bottle that form no part of the claimed design.

1 Claim, 3 Drawing Sheets*FIG. 1*

FIG. 2

FIG. 3
